Primary Examiner — Robert A Delehaney

(57) CLAIM

The ornamental design for a silicone sink splash guard, as shown and described.

DESCRIPTION

FIG. 1 is a front perspective view of a silicone sink splash guard, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,
FIG. 7 is a bottom view.
